CLAIM

The ornamental design for a pill organizer, as shown and described.

DESCRIPTION

FIG. 1 is a front, right, and top perspective view of a pill organizer, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a perspective view of the pill organizer of FIG. 1 wherein a lid of the pill organizer is open; and,

FIG. 9 is an exploded view thereof.

1 Claim, 9 Drawing Sheets
